DEVICE FOR BREAKING BOTTLES

Anders R. Lofstrand, Sr., Washington, D. C.

Application December 14, 1936, Serial No. 115,868

2 Claims. (Cl. 83—93)

This invention relates to a device for breaking bottles.

Federal laws prohibit the re-use of containers that have been filled with spirituous liquors. The most satisfactory way to insure that this provision shall be carried out is breaking the bottle in which liquor of this kind is usually sold, so that its further use becomes impossible.

With this end in view, the purpose of the present invention is to provide a device that can be employed to break bottles quickly and neatly. In places such as restaurants and drinking establishments, the accumulation of empty bottles becomes a major problem. Therefore, the purpose of the present device is to provide means whereby bottles may be quickly broken with a minimum of effort, with no scattering of the broken pieces and with safety.

A further object of the invention is to provide a device of the class named which is simple and sturdy in its construction, relatively inexpensive to manufacture, easy to operate and thoroughly efficient in accomplishing its purpose.

These and other objects which will become more readily apparent as the description progresses are attained by the novel construction and combination of parts hereinafter described and shown, forming a material part of the disclosure, and in which:

Figure 1 is a front elevation of the invention showing the manner in which it is applied to a bottle for breaking the same.

Figure 2 is a vertical sectional view, and

Figure 3 is a horizontal sectional view taken on line 2—2, Figure 2.

The device includes a tubular shank element 1 of the desired length and diameter, a combined abutment and shield element 2 and a combined plunger and breaking element 3.

Element 1 is formed from any suitable material, preferably metallic, and is provided with outer peripheral threads at one end terminal portion 4 and with outer peripheral threads at the other end terminal portion 5 thereof.

Element 2 is formed of any suitable material and includes a body 6 of arcuate cross section. The body 6 is of the desired length and width, formed with enlarged end terminal portions 7, 8 and provided with an opening 9 intersected by the transverse and longitudinal medians thereof. The wall of opening 9 is threaded. The outer face of body 6 has an annular boss 10 having its inner edge threaded. The threads on the inner face of boss 10 form continuations 55 of the threads on the wall of opening 9. Ex-

tending radially from the boss 10 and integral with the outer face of body 6 is a series of reinforcing ribs 11.

The peripheral threaded end terminal portion 4 of the element 1 engages with the threads on the wall of opening 9 and inner edge of boss 10 whereby elements 1 and 2 are anchored together.

The element 3 includes a solid rod 11 of the desired length and diameter and preferably of 10 circular cross section. Rod 11 is formed of any suitable material, preferably hard metal. The diameter of rod 11 is materially less than that of the inner diameter of element 1. One end projects through opening 9 of shield 2 and is 15 pointed as at 12. The other end terminal portion of rod 11 is fitted with a gripping member 13 which is preferably of a substantially globular form.

At its upper end terminal portion 5, tube 1 is 20 provided with a cap member 14 of substantially cup-shape form whose inner periphery is screw-threaded to engage threads on the outer periphery of upper end terminal portion 5 of tube 1. Cap member 14 is provided with a circular opening 15 of substantially smaller diameter than the inner diameter of tube 1. The diameter of opening 15 is sufficiently larger than the diameter of rod 11 to enable said rod to pass through it while preventing any substantial lateral motion of rod 11. The opening 15 and the tube 1 are concentrically arranged with respect to each other.

The inner face of cap member 14 forms a shoulder 16 adjacent to opening 15, which shoulder acts as an abutment for one end of a spiral spring 17. Spring 17 surrounds rod 11 within tube 1. At its other end spring 17 abuts against a collar 18, which is concentric and integral with rod 11 but of substantially greater diameter. 40 It is formed intermediate the ends of rod 11. It is of a diameter sufficiently smaller than the inner diameter of tube 1 to allow it to move freely vertically within the tube, but its diameter is great enough to prevent any substantial 45 lateral motion of rod 11.

The outer face 19 of cap member 14 forms an abutment for a spiral spring 20 which surrounds the part of rod 11 projecting from the upper end of tube 1. At its other end, spring 20 abuts 50 against the lower face 21 of gripping element 13.

Spring 17 in its normally expanded position acts to keep rod 11 extended through opening 15. In operation, tube 17 is held by one hand of the operator while with the other knob 13 is pulled 55

against the action of spring 17 until the point 12 of rod 11 is pulled through opening 15 into tube 1. Shield 2 is then placed against the bottle 22 which it is desired to break, and knob 13 is released, thus 5 allowing spring 17 to force rod 11 out through opening 15 with sudden force. The sharpened point 12 of rod 11 will strike the bottle with sufficient force to smash it as indicated in dotted lines, Figure 1. Shield 2 will prevent particles of 10 glass from flying upward, while spring 20 will act as a shock absorber and will counteract to some extent the expansive action of spring 17.

What I claim is:—

1. In a bottle breaking device, a convexo-concave shield of greater length than width and being formed at the intersection of its transverse and longitudinal medians with a boss having an opening having a threaded wall, ribs arranged at right angles to each other reinforcing the sides 20 of the shield and connecting the same to the boss, a tubular casing threaded into said boss, a plunger provided at its inner end with a bottle breaking means for extension through said casing and shield; said plunger of less length than said 25 casing, an axially apertured cap on the outer end of the casing and through which extends the outer portion of said plunger, a collar on the plunger intermediate the ends of the latter, a plunger forcing spring within the casing and interposed 30 between the collar and cap, a hand grip on the other end of the plunger, and a spring encompassing the plunger and interposed between said grip and cap.

2. An apparatus of the class described including 35 a straight solid shield for positioning and con-

fining a bottle to prevent pieces being forced in undesired directions, said shield comprising a body unobstructed at its ends and of greater length than width and curved only in the direction of its narrow dimension whereby the sides may be 5 prolonged to a desirable extent to prevent particles flying and injuring an operator, said shield at the intersection of its transverse and longitudinal medians having a boss containing a central opening with an internally threaded wall and 10 strengthening ribs arranged at right angles to each other reinforcing the sides of the shield and connecting same to the boss, a lengthened tube forming a shank threaded at both ends engaging at its lower end with said threaded boss and its 15 upper extremity closed by a central perforated cap engaging the upper screw threads, a round sharpened rod of less diameter than the shank providing a bottle breaking means for extension through said shield, and a collar attached to the 20 rod for guiding and operating the latter, a long spiral expansion spring encompassing the rod above the collar and contacting the latter and bearing at its top against the under side of the aforesaid cap, with a short spiral spring bearing 25 against the opposite or outer portion of the cap, encompassing the rod, an operator's grip on the extreme upper end of the rod and designed to engage said last named spring only when the rod is forced downward by first named spring and 30 forming a shock absorber therefor, the total length of the shank being greater than the distance from the grip to the top of the collar.
